UNITED STATES PATENT OFFICE

JACQUELYN HAWTHORNE ATHANA, OF NEW YORK, N. Y., ASSIGNOR TO LEANDER DEVELOPMENT CORPORATION, OF NEW YORK, N. Y., A CORPORATION OF NEW YORK

DESIGN FOR A HEAT INDICATOR FOR AUTOMOBILES

Application filed October 31, 1930. Serial No. 37,482. Term of patent 14 years.

To all whom it may concern:

Be it known that I, JACQUELYN HAWTHORNE ATHANA, a citizen of the United States of America, residing at New York city, New York, have invented a new, original, and ornamental Design for Heat Indicator for Automobiles, of which the following is a specification, reference being had to the accompanying drawings, forming part thereof.

Figure 1 is a front elevation of a heat indicator for automobiles embodying my new design.

Figure 2 is a side view of the same.

I claim:

The ornamental design for a heat indicator for automobiles, as shown.

In testimony whereof I have signed my name to this specification.

JACQUELYN HAWTHORNE ATHANA.
